UNITED STATES PATENT OFFICE.

HORACE E. WOOLERY, OF ST. PAUL, MINNESOTA.

RAILWAY MOTOR CAR.

Application filed July 24, 1922, Serial No. 577,216. Renewed September 28, 1925.

To all whom it may concern:

Be it known that I, HORACE E. WOOLERY, a citizen of the United States, residing at St. Paul, Ramsey County, Minnesota, have 5 invented certain new and useful Improvements in Railway Motor Cars, of which the following is a specification.

My invention relates to certain improvements in the design and construction of 10 railway motor cars ordinarily used by bridge and section men of railway companies in the ordinary course of maintenance of lines of railroad.

My objects are to provide a motor driven 15 four wheeled railway car of light weight, simple of construction, safe in operation, and economical of manufacture, equipped to carry railway employees with their tools and repair materials from place to place, 20 in the repair and up-keep of lines of railroad.

Figure 1 is a perspective view of such a car, equipped and mounted on the rails. Figure 2 is a transverse cross sectional view 25 at a point near the forward end of the car. Figure 3 is a longitudinal cross sectional view taken on a line *a—a* of Fig. 2, and looking in the direction of the arrow, to show principally one of the longitudinal 30 sill members with truss and truss posts.

The car follows generally the usual lines of the ordinary section car equipped with an engine for the propelling power, but has certain outstanding features which distinguish it as superior to cars in similar use, which are briefly stated as follows: It is provided with a semi underslung frame, of fairly light yet quite rigid construction. The two principal longitudinal sill members 35 completed comprise the timbers (1), preferably made from hard maple one and one quarter inches by five and one half inches; steel channel truss members (2), preferably of a dimension of one and one half inches by three quarters of an inch; the truss posts in the several positions as shown and as follows:—center truss posts of gas pipe 40 (5), the next outer truss posts of timber (4), which are preferably of hard maple of a dimension of one and one quarter 45 inches by four and one half inches, and which timbers also form the two cross sills of the car frame; and the outer two truss posts (3), which also constitute the running boxes and bearings in which the car axles 50 (8) run. The turned-up or trussed ends of

the channels (2) are secured to the outer timber sill members (1) by means of ordinary bolts with nuts, which bolt fastenings also serve to secure in positive position a 60 piece of gas pipe of suitable dimension, and termed a hand lift (6), which is fitted between the outer ends of the two outside longitudinal sill timbers (1), as shown in Figure 1. Each end of the car is fitted with 65 these hand lifts (6), which are also termed guards, and are designed to accomplish two things; first they guard the hands of employees when they are moving the car from the rails, and second they serve as stiffeners 70 to hold the car frame in a rigid condition. By being placed about three inches outward from the two outside cross timbers (17) of the car frame and about the same distance from the top of said frame timbers (17), downward, the hands of the employees are more secure from being injured 75 during the operation of removing the car from the rails, as by this construction it is possible to tilt the car endwise without 80 crushing the hands of employees under the car frame.

By turning up the ends of the truss channels (2) and securing them to the beveled ends of the sill timbers (1), the car may 85 be tilted endwise to a large degree or the wheels may drop into holes during the removal operation, without injuring employees or making such removal a difficult or dangerous operation, by reason of these 90 hand guards or stiffeners.

By using the bearing blocks mentioned, which are housed between the sill timbers (1) and the channels (2) I have the benefit 95 of using them as truss posts and at the same time I secure a low center of gravity and a low car floor, yet with ample clearance, which makes this car convenient and easy to handle, as well as easy and safe to mount. The lower the center of gravity, with adequate clearance, the faster the car may be 100 operated with safety.

Another distinctive feature is the spacing of the wheels to provide a wheel base on the rails of forty inches, or in other 105 words the axles of the car wheels are spaced forty inches from center to center of their longitudinal center lines. Ordinary pressed steel car wheels of the usual type, but only twenty inches in diameter are used, being 110 fitted onto their respective axles of chrome nickel steel in pairs in the customary way.

By using a minimum of forty inches for a wheel base and twenty inch wheels I prevent all four wheels from simultaneously dropping between the rails when the car is turned to a position that is transverse to the center line of the track. This is distinctly a safety measure in the interest of employees, because while one pair of wheels is down inside of and against one rail, the other pair of wheels is resting nearly on top of the opposite rail and is in a position to be easily moved outward and away from the track. This applies to the standard gauge of track which is four feet eight and one half inches. It frequently happens that speed in the removal of such a car from the track is necessary. This spacing and construction makes for speed in removal when such is needed.

In making up the housing for the engine, I do several things of advantage. I provide rather deep tool trays on each side of the car; the inner sides of the tool trays, being the inner longitudinal sill members of the car, form at the same time partial side guards for the engine and tool tray sides. These are fabricated in the usual way with ordinary bolts with nuts and such screws as may be needed. The housing further consists of a suitable timber bench (14), supported by a timber stringer (15) running lengthwise under each outer edge of the timber bench (14), which supporting stringers (15) are secured to four upright tubular members (12) which are secured to the two end frame timbers (17) preferably by means of ordinary bolts with nuts attached. Extending downward from the supporting stringers (15) I use steel plates of about one eighth of an inch in thickness and approximately eighteen inches in length, which steel plates (16) are screwed to the supporting stringers (15) and to the inner sides of the inside timbers of the tool trays. I prefer to make the tool trays the full length of the car and about five and one half inches deep, without guards front or back, except the ends of the trays as shown, so as to permit the carrying of steel rails, timbers or other material of greater length than the length of the car; and also this depth is used for protection of tools from loss by falling from the trays while the car is in motion. The floors of the tool trays are laid on top of the two cross sill timbers (4) and at each end rest on angled steel pieces fastened to the inner faces of the two end frame members (17). These floors are timber, but other suitable material could be used.

Referring again to the bench (14) of the housing, I prefer to use angled steel pieces (13) welded between the upright tubular supports (12) as the main supporting members for the timber bench (14), although

other material and other methods of fastening or securing such cross supporting members could be used.

All tubular railing and supporting or guard members are of pipe of an approximate diameter of three quarters of an inch. In case of the two front tubular members (12), I bend them outward from the longitudinal center line of the car, carrying them at right angles out to a point which is sufficient to over reach the tool trays on each side of the car, thence upward at right angles a distance of twelve or fourteen inches, then again bend them at right angles toward the longitudinal center line of the car to said center line, at which point I locate a connecting tubular member (18), welding the end thereof to the front tubular members (12). The opposite end of this connecting longitudinal tubular member (18) is welded to the rear tubular members (12) at the same elevation as at the front end of the car. The rear tubular members (12) with the angled piece of steel (13) are the rear supports for the bench (14) portion of the housing. After carrying these tubular rear members (12) as uprights to the same elevation as the front members (12) where they meet and are welded to the connecting longitudinal tubular member (18) I bend them toward the longitudinal center line of the car, carry them to that line and weld them to said connecting tubular member (18) at that point.

The said tubular members, both (12) and (18), which are disposed upward and outward from the bench (14) and above and longitudinally with said bench (14) form hand-holds or grips for the employees, or against which said employees may lean, if desired. The front portions of the tubular members (12) which are extended outward and over the front end of the tool trays are so disposed to form a further guard for employees to prevent them from falling in front of the car while it is in motion.

The timber bench (14) with its tubular supports (12), connection tubular member (18), steel angles (13) and steel housing and guard plates (16) are all so arranged and fabricated together that they form an independent unit; but at the same time provide lightness of weight with rigidity of construction, means of safety to employees in the operation of the car, and by removing of a very few bolts and screws these portions may be removed as a single unit from the car.

Employees are further protected from the car wheels by my use of four crescent shaped wheel guards (11), made from a medium weight of metal and screwed to the outer sides of the two longitudinal sill members (1) at the proper points. I further protect those who may use this car by housing the

belt drive. I place the engine a little to the rear of the car and drive from the front axle with a suitable drive pulley and belt, as I contend that greater results are obtained by placing the power to operate the car by pulling it than could be obtained by locating the engine and drive to apply a pushing power.

The power is derived from one of my own gasoline engines, secured to the regular engine plank or mounting in the usual way, which plank is in turn bolted or otherwise suitably fastened securely to the floor of the car, and resting particularly on the two cross sill members (4). Any other engine of sufficient power development may be used.

I claim:

1. In a railway motor car the combination with the running parts and car floor and inner and outer longitudinal sill members and front and rear cross frame timbers, of timber and tubular housing mem-

bers with metal engine guards disposed downward and between said timber housing 25 and the inner longitudinal sill members, said tubular members bolted to the front and rear cross frame timbers.

2. In a railway motor car longitudinal sill timbers provided with beveled ends and 30 stiffened by steel channels contacting said beveled portions, with tubular cross members disposed between the outer ends of the outer longitudinal sill timbers.

3. In a railway motor car the combination 35 with the running parts and car floor, of tubular supports for a timber engine housing and seat bench with steel angles disposed between the upright portions of said tubular supports, which front supports are 40 extended outwardly from the center longitudinal line, thence upward at right angles, thence back to said center line to a center tubular connection with the rear tubular supports for said timber engine housing.

HORACE E. WOOLERY.
